UNITED STATES PATENT OFFICE.

ARTHUR O. HUBBARD, OF MINNEAPOLIS, MINNESOTA.

SILO-DOOR.

1,090,620.

Specification of Letters Patent. Patented Mar. 17, 1914.

Application filed April 25, 1913. Serial No. 763,537.

To all whom it may concern:

Be it known that I, ARTHUR O. HUBBARD, a citizen of the United States, resident of Minneapolis, Hennepin county, Minnesota, have invented certain new and useful Improvements in Silo-Doors, of which the following is a specification.

The object of my invention is to provide combined ladder rungs and hinges for the silo doors by which the weight of the person climbing the wall of the silo will be thrown directly upon the doors and their bearings.

A further object is to provide an improved construction of ladder and hinge which will be more secure and substantial than devices of this kind ordinarily employed for this purpose.

The invention consists generally in various constructions and combinations, all as hereinafter described and particularly pointed out in the claims.

In the accompanying drawings forming part of this specification, Figure 1 is a front elevation of a portion of a silo, showing my invention applied thereto, Fig. 2 is a perspective view, showing in detail the manner of mounting the silo door on the wall of the silo, Fig. 3 is a vertical sectional view, showing the supports for the doors when closed, Fig. 4 is a horizontal sectional view through the silo door and wall of the silo, showing the door in its closed position, Fig. 5 is a similar view, showing the door in its open position.

In the drawing, 2 represents the wall of the silo and 3 and 4 the upright posts on each side of the door opening. The space between these posts is divided transversely at intervals by cross bars 5 having longitudinal rabbets 6 and 7 on their inner faces, which are adapted to receive respectively the upper and lower edges of the doors 8, the inner surfaces of the doors being flush substantially with the inner wall of the silo when the doors are closed.

For supporting each door and for convenience in ascending the wall of the silo, I provide for each door a combined hinge and ladder or step consisting of a single rod having a vertical middle portion 9 that is pivotally supported at its upper and lower ends by means of hinge straps 10 secured to the door post 3 at one side of the opening. The upper end of the part 9 has an end portion, preferably integral therewith, that is out-

wardly turned at 11 and provided with a horizontal continuation or part 12 that is parallel substantially with the plane of the door and spaced therefrom a sufficient distance to form a step or ladder rung. A part 13 forms an inwardly inclined extension of the part 12, terminating in a hook portion 14 that is fitted into a vertical socket 15 provided in the cross bar 16 of the door and having an outwardly turned end 17 which locks the part 14 securely in the cross bar. The inner portion of the part 13 rests on the upper edge of the cross bar 16 and is supported thereby in a substantial manner. The lower end of the part 9, after passing through the hinge strap 10, has an outwardly bent portion 11a and a horizontal continuation 12a thereof forming another rung of the ladder, and an inwardly extending part 13a fitting within a socket in a cross bar 16a in substantially the same manner as described with respect to the cross bar 16. The bearings of these hinge rods are near the middle of the door, as indicated in Fig. 1, and the load or weight of the person on the rungs in ascending or descending is sustained for the most part by the cross bars and is transmitted from them through the door to the seat thereof beneath the lower edge of the door.

Usually in devices of this kind the hinge rungs or steps are secured to the door by clips or plates fastened by screws or like means and it often happens that these screws are pulled out or broken or the plates are damaged in such a way that it is dangerous for a person to ascend or descend the ladder, but I have found with this device that the manner of mounting the hinge rods on the cross bars of the door is so substantial that it is impossible for the rungs to become detached at this point and the comparatively broad sheet metal plates or straps 10 insure the permanent mounting of the rods on the frame of the door. The outwardly turned portions 11 and 11a are sufficiently long to set the horizontal sections of the rods away from the silo and at the same time, as indicated in Fig. 5, allow the door, when swung inwardly, to be moved to a position against the wall of the silo. The part 9 and the end portions thereof being formed of one piece of wire rod, suitably bent, not only provide a very economical and durable construction; but cannot be

pulled off the door by the weight of the person climbing the ladder, as might happen where the rungs are fastened by screws and plates or clips to the door. In such cases the weight of the person is thrown upon the screws or other fastening means and often these will become corroded and break off or pull out of the door. By forming the hinge member and the two rungs of each door in one piece, the load is transmitted through the door to its bearings and the rungs will always be held firmly in place under all conditions.

For holding the door in its closed position any suitable means may be provided. I prefer, however, to provide a plate 18 on one side of the door, having a pointed end 19 adapted to enter a socket 20 in the door post 4. On the other side a pivoted latch 20, 21 is provided, having a cam surface at one end adapted to enter a slot 22 in the post 3, thereby drawing the door snugly to its seat.

The ladder rungs may be set out any suitable distance from the door to allow foot room in ascending or descending the silo, and the rungs may be arranged any suitable distance apart, preferably about $7\frac{1}{2}$ inches from center to center.

30. The rods can be easily bent to the desired form and can be easily assembled with the doors, and will not only form durable hinge members for the doors, but will provide

very substantial rungs or steps for the person ascending the silo.

35

I claim as my invention:

1. The combination, with a silo having a door opening and a door therefor, provided with cross bars and sockets therein, of a hinge supported on the frame of said door 40 and having end portions which extend in front of the door and spaced therefrom to form ladder rungs, said end portions being seated on said cross bars and supported thereby and having ends fitting within said 45 cross bar sockets.

2. The combination, with a silo having a door opening and a door therefor provided with cross bars and sockets therein, of a combined hinge and ladder consisting of a 50 single rod having an upright middle portion and means supporting it at one side of the door opening, said rod having end portions which extend in front of the door and are spaced therefrom to form ladder 55 rungs, said end portions being seated on said cross bars and supported thereby and having ends fitting within said cross bar sockets.

In witness whereof, I have hereunto set 60 my hand this 19th day of April 1913.

ARTHUR O. HUBBARD.
